MEANS FOR SMOOTHING SLEEVED ARTICLES ON PRESSING TABLES AND THE LIKE

Floyd A. Wiegman, Chicago, Ill., assignor to The Prosperity Company, Inc., Syracuse, N. Y., a corporation of New York

Application March 7, 1939, Serial No. 260,350

18 Claims. (Cl. 38—12)

This invention relates to a means for smoothing sleeved articles on pressing tables.

The means comprising this invention relates to ironing machines or ironing boards or the lower pressing elements of pressing machines, and has for its object a particularly simple means for automatically taking the slack out of tubular articles to be ironed. Further, due to the inherent characteristics of said means sufficient tension is automatically applied to smooth out in a lateral direction the portion of the article overlying the table or pressing element, and take up the slack in the article, as, and after, the article is sleeved on the table or pressing element. The tubular articles may be the sleeves of shirts or other articles, such as trouser legs, etc.

The invention further has for its object means as a clamp for holding one end of the sleeved article on the face of the pressing element to permit manual longitudinal stretching of that portion of the sleeved article overlying the pressing element to be pressed, after the slack is taken up in lateral directions automatically by the said means during and after the sleeving of the article on the pressing element or table.

It further has for its object a means for this purpose consisting of a member including a series of independently movable units of inherent characteristics arranged so as to uniformly and automatically conform to the inner surface of the article and to bear on the inner face of the lower portion of the article hanging under the table or pressing element and thereby smooth the article on the face of the pressing element.

A further object of the invention is the provision of means to simultaneously and automatically take up slack in the tubular article below the pressing surface and smooth a portion of the same on the pressing surface without manual operation and/or attention, yet permitting the article to be turned or rotated about the pressing surface without removing the same from the latter to present a new surface to be pressed while the said means, without manual operation and/or attention due to its inherent characteristics continues during such rotating of the article about the pressing surface to automatically, in the absence of manual attention and/or operation, to simultaneously exert pressure to take up the slack below the pressing surface and smoothing of that portion of the article overlying the pressing surface.

Further, it is an object of this invention to provide a new and improved method of smoothing sleeved tubular articles on pressing tables and

the consequent complete pressure ironing of said articles thereon.

Another object of the invention resides in the method of completely pressure ironing including sleeving of the article on the pressing surface; effecting simultaneous slack take-up of said article below the pressing surface and smoothing of that portion of the article overlying the pressing surface; the necessary manual rotating movements of the article by an operator about or on the pressing surface to present new surfaces to be pressed without removing the article therefrom, and without any manual operation except rotating of the article by the operator, and simultaneously with such rotating operation of the article effecting continuous slack take-up of the article below the pressing surface and smoothing of that portion of the article overlying the pressing surface.

20 The invention consists in the novel features and in the combinations and constructions herein-after set forth and claimed.

In describing this invention, reference is had to the accompanying drawings in which like characters designate corresponding parts in all the views.

Figures 1 and 2 are respectively a front elevation and a side elevation of a pressing machine embodying my invention.

30 Figure 3 is an enlarged elevation of the lower pressing element or table of a pressing machine provided with this invention, showing a shirt with the sleeve sleeved over the pressing element.

Figure 4 is a fragmentary view similar to Figure 3 and partly in section, showing slightly different embodiment of the invention.

40 1 designates the pressing table, which in pressing machines is the lower pressing element or buck with which coacts a movable pressing element or head 2. The pressing table or lower pressing element 1 is supported from one end thereof from the frame 3 of the machine by a bolster or so-called goose neck 4, so that the greater portion of the table or pressing element 1 overhangs for permitting an article to be sleeved thereon. These articles, as for instance the sleeves of a shirt taper from a larger diameter at the shoulder end to a smaller diameter at the cuff end.

45 50 The means for taking up the slack in the portion of the article hanging over the sides of the table or pressing element, and hence for smoothing out in a lateral direction the portion of the article laid on the table, in the illustrated embodiment of the invention, comprises a member

flexibly suspended at its ends from opposite ends of the table beneath the same, so that the intermediate portion bears on the inner surface of the portion of the article or sleeve hanging below the table or pressing element 1 substantially throughout the length of said article or sleeve, and regardless of the taper of the article.

5 designates the member flexibly suspended at its ends beneath opposite ends of the table, the member 5 being flexible throughout its length and consisting of connected links 6 comprising a chain, which is secured at 7 and 8 beneath the table or pressing element 1 near opposite ends thereof, and which normally hangs slack. The individual links of the chain constitute a series of independently movable units arranged to rest on the inner face of the lower portion of the article sleeved on the table and draw the same fairly taut over the table or pressing element 1 and take up the slack in the portions of said article overhanging the table or pressing element 1. Obviously, when the sleeve is sleeved over the table 1, the flexible chain 5 will press, by its weight, on the lower portion of the sleeve, and the individual links apply the weight so that the weight of the chain is evenly distributed throughout the overhanging sides of the article.

In Figure 4, the flexible member is designated 9 and consists of a strand secured at 10 and 11 beneath opposite ends to the under side of the table or pressing element 1 and a plurality of weights 12, here shown as perforated balls, strung on the strand 9. These balls are also individual units similar to the links 6 of the chain.

In any form of the invention, a member for taking up the slack in the overhanging sides of an article sleeved on a table or pressing element and for drawing it smooth over the face of said table or element is flexibly suspended at its ends beneath the opposite ends of the table or pressing element 1 and is capable of a free vertical movement to conform to the interior contour or the taper of the sleeved article.

The pressing machine is preferably provided with a clamp 27 for coating with one end of the sleeved article. The clamp is particularly adapted for shirt sleeves and to clamp the cuff, which usually has been previously ironed, to the outer end of the pressing element 1, so that after the sleeve is sleeved over the pressing element and the clamp applied, the operator can pull the sleeve and stretch and smooth it in a lengthwise direction on the pressing element. The chain 5 or member 9, in applying their weight to the inner surface of the overhanging portion of the article, smooth the article in a lateral direction relative to the table 1.

The clamp 27 is embodied in the machine in any suitable manner, it being here shown as carried by one arm of a lever 28 pivotally mounted at 29 to an upwardly extending arm 30 on the frame 3 of the machine, and is actuated into operative position by a pedal lever 31 pivoted at 32 to the base of the machine and connected by a link 33 to one arm of a lever 34 pivoted between its ends at 35 to the frame of the machine and connected at its other end by a link 36 to an arm 37 on the lever 28 and extending beyond the pivot 29. The movement of the pedal is against the action of a suitable returning spring 38.

The press head 2 of the machine is carried by a suitable lever or yoke 39 pivoted to said upstanding arm 30 on an axis coincident with

the axis 29. The head-carrying lever 39 is actuated in any well known manner.

In operation, when the press is open, that is, when the press-head is up, and also when the clamp 27 is in its open or upper position, indicated in broken lines (Figure 2), the operator sleeves the article on the pressing element or buck 1, and then depresses the pedal lever 31 to bring the clamp 27 down on the end of the article, this being the cuff of a shirt sleeve. The operator then stretches the sleeve lengthwise of the pressing element or buck 1 by pulling the sleeve from the shoulder end against or away from the clamp. As the sleeve is sleeved on the pressing element or buck 1 and after it is laid on the element or table 1, the flexible member 5 or 9 of this invention automatically takes up the slack in a lateral direction and smooths the sleeve or the portion thereof lying on the pressing face of the element or buck 1. After one lengthwise portion of the sleeve has been pressed, the press and clamp are opened, the sleeve is shifted around the pressing element to bring another portion of the pressing face, and the operation repeated.

25 What I claim is:

1. The combination with a pressing table supported at one end so that the greater portion of the table overhangs for permitting an article to be ironed to be sleeved over said table, and means located beneath the overhanging portion of the table for entering the article when being sleeved thereon and conforming to said article to take up the slack in the portion of the article hanging from the table and to smooth the portion on the table, said means comprising a flexible member suspended at its ends from opposite ends of the table on the under side thereof and a series of weights strung on said member along the length thereof.

2. The combination with a pressing table supported at one end so that the greater portion of the table overhangs for permitting an article to be ironed to be sleeved over the table, means located beneath the overhanging portion of the table for entering the article while the article is sleeved thereon and extending entirely therethrough and automatically taking up the slack in lateral directions in said article, said means comprising a flexible member suspended at its ends beneath the table and a series of weights strung on said member along the length thereof, and means for holding the portion of the article on the table at one end thereof for permitting stretching of the article while being held at one end.

3. The combination with a pressing table adapted to receive a tubular article, and flexible gravity actuated chain article slack take-up means substantially coextensive with the under-side of the pressing table, said means extending entirely through and engaging an interior portion of the tubular article below the table and automatically adapting itself to the engaged interior contour of said article thereby uniformly taking up slack in the article hanging from the table and maintaining that portion of the article on the table in a smooth condition.

4. The combination with a pressing table supported at one end so that the greater portion thereof overhangs for permitting an article to be ironed to be sleeved thereon, and movable flexible gravity actuated means located beneath and substantially coextensive with the pressing table and extending within the article, said means automatically effecting a smoothing of that portion

tion of the article on the pressing table, and a taking up of the slack of that portion of the article below the table without manual operation of said means and permitting rotation of the article on the table to present another portion of the article to be ironed without manual operation of said means or removal of the article from the table and permitting removal of the article from the table without manual operation of said means.

5. The subject matter of claim 4, and means for holding a portion of the article on the table at one end thereof for permitting stretching of the article while being held at said end.

6. The subject matter of claim 4, including a movable pressing head for cooperation with the pressing table.

7. The subject matter of claim 4, wherein the said means is a gravity actuated chain.

8. The subject matter of claim 4, wherein the said means is a gravity actuated chain attached at each end thereof adjacent opposite ends of the underside of the pressing table and hanging loosely intermediate its ends therebelow.

9. The combination with a pressing table supported at one end so that the greater portion of the table overhangs for permitting an article to be ironed to be sleeved over the table, and movable flexible gravity actuated means located beneath the table for entering the article when being sleeved thereon and conforming to said article to automatically take up the slack in the portion of the article hanging from the table and to simultaneously smooth the portion on the table without manual operation of said means, and permitting rotation of the article on the table to present another portion of the article to be ironed, without manual operation of said means or removing the article from the table, and permitting removal of the article from the table without manual operation of said means.

10. The subject matter of claim 9, and clamping means for holding a portion of the article on the table at one end thereof for permitting stretching of the article while being held at said end.

11. The subject matter of claim 9, including a movable pressing head for cooperation with the pressing table.

12. The subject matter of claim 9, wherein the 50 said means is a gravity actuated chain.

13. The subject matter of claim 9, wherein the said means is a gravity actuated chain attached at each end thereof adjacent opposite ends of the underside of the table and hanging loosely 5 intermediate its ends therebelow.

14. The combination with a pressing table supported at one end so that the greater portion thereof overhangs for permitting an article to be ironed to be sleeved over the table, and flexible 10 gravity actuated chain article slack take-up means located beneath the table for entering the article when being sleeved thereon and conforming to the said article to automatically take up the slack in the portion of the article hanging from the table and to simultaneously smooth the portion on the table without manual operation of said means and permitting rotation of the article on the table to present another portion to be ironed without manual operation of said means or removing the article from the table, and permitting removal of the article from the table without manual operation of said means.

15. The subject matter of claim 14, and means for holding a portion of the article on the table at one end thereof for permitting stretching of the article while being so held.

16. The subject matter of claim 14, including a movable pressing head for cooperation with the pressing table.

17. The subject matter of claim 14, wherein said chain is attached at each end thereof beneath opposite ends of the table and hangs loosely in loop formation intermediate its attached ends.

18. The combination with a pressing table supported at one end so that the greater portion thereof overhangs for permitting an article to be ironed to be sleeved over the table, and flexible gravity actuated chain article slack take-up means located beneath the table and conforming to the said article to automatically take up the slack in the portion of the article hanging from the table and to simultaneously smooth the portion on the table without manual operation of said means and permitting rotation of the article on the table to present another portion to be ironed, without manual operation of said means or removing the article from the table and permitting removal of the article from the table without manual operation of said means.

FLOYD A. WIEGMAN.
